United States Patent Office

Des. 182,358
Patented Mar. 25, 1958

182,358

TYPEWRITER

Laird Covey, Monroe, Conn., assignor to Royal McBee Corporation, Port Chester, N. Y., a corporation of New York

Application June 25, 1957, Serial No. 46,721

Term of patent 7 years

(Cl. D64—11)

Fig. 1.

Fig. 2.

The essential features of my design for a typewriter reside in the parts shown in full lines.

What is claimed is:

The ornamental design for a typewriter, substantially as shown and described.
